UNITED STATES PATENT OFFICE

2,135,781

DRYING UNIT

Patrick Joseph Murray, Clifton Heights, Pa., assignor to Trisco Products, Inc., Philadelphia, Pa., a corporation of Pennsylvania

Original application August 29, 1936, Serial No. 98,571. Divided and this application May 28, 1937, Serial No. 145,224

5 Claims. (Cl. 223—77)

The present unit relates to a device intended for any use for which it proves suitable, but having its present best and widest use in the drying of stockings after washing and re-treatment by the individual users, making it possible to make the stockings look like new. It is applicable also to fine underwear.

This application is a division of application Serial No. 98,571, filed August 29, 1936, for 10 Laundering unit for silk hosiery.

A purpose of the invention is to provide carrying mounts for the drying of stockings.

A further purpose is to spring-clamp forms for stretching and drying washed and treated stockings to a base which mounts a receivable for 15 washing and treating them.

A further purpose is to position a stocking drying form on a radiator or other heating device by a removable base which directs warm air to 20 dry stockings, boarded on the form.

Further purposes will appear in the specification and in the claims.

One main form only of the invention is shown 25 selecting a form which is practical and efficient in operation and which well illustrates the principles involved.

Figure 1 is a sectional plan of structure embodying a desirable form of the invention.

Figure 2 is a front elevation of the structure of 30 Figure 1.

Figure 3 is a section of Figure 2 taken upon the line 3—3 thereof.

Figure 4 is a reduced scale view corresponding 35 to Figure 2 but illustrating in its entirety a stocking form shown as a fragment only in Figure 2.

Like numerals refer to like parts.

Describing in illustration but not in limitation and referring to the drawings:

The construction of the washing vessel is not 40 important to the present case, and the particular construction shown is merely illustrative.

A duplex washbowl or flask 10, of preferably dumb-bell shape, shown to best advantage in Figure 2, comprises two interconnected individual 45 bowls 11 and 12 connected by a waist, closed at one end at 13 and open at the opposite end at 14, except as closed by any suitable cap 15. Each individual bowl preferably is large enough to contain all of the articles intended to be washed 50 at one time so that as the duplex bowl or flask is rocked or shaken by the hands of the user the articles to be washed may be shifted from bowl to bowl across the intervening waist 17.

In order that the washing may be as fully 55 effective as possible the waist area and desirably

also some part or all of each of the bowls are internally so surfaced as to produce a washboard effect. This washboard surfacing of the interior of the waist is shown in the form of corrugations 18 comprising projecting ribs and 5 grooves 21. As shown at 22, part of each bowl need not be covered with corrugations.

Because it is very desirable that the progress of the operation may be watched to advantage from the exterior, the flask if not made from 10 glass will normally be made of a highly transparent resin.

The duplex bowls are shown as provided with flattened bottom sections upon which conveniently the flask may be rested. These are 15 secured by altering the contours of the corrugations, as at 33, 34. The end 13 is also flattened as at 35 so that the flask may rest upon it.

The flask is conveniently mounted upon a stand 36 having a top 37. Clips 38 and 39 engage 20 the flask at a convenient place preferably at the waist and retain the flask against lateral movement. The clips 38 and 39 are spring clips so that the flask may be held within any resilient restraint desired. In the illustration these clips 25 are given an added function in that they are curved outwardly and circularly at 40 and 41 to receive collapsible tubes 42 and 43 within which washing and treating materials are contained. The spring clips end at 44 and 45 in tabs which 30 may be engaged by the hands of the user to expand the curved portions of the clips so that the tubes 42 and 43 may be removed to the best advantage. However, the contents of the tubes 35 may be pressed from them, while the tubes are in place, by winding up keys 46.

The stand 36 is slotted in suitable points 47, 48, 49 and 50 corresponding in number with the desired number of drying forms 51 to be supplied so that these forms may be inverted and held in 40 position for use.

As illustrated the forms 51 are constructed of wire united at the end of the leg portions by fittings 52, fastened each rigidly to one leg portion as 53 and transversely directed at the otherwise 45 open ends 54 of the fittings so as to receive and frictionally to engage extensions 55 of the other sides 56 of the leg portions of the forms.

The extensions 55 are intended to pass within the open ends 54 to varying extents according 50 to the size of leg portion of the stocking to which the individual form is to be accommodated.

Whatever the adjustment of the leg width determined upon, the extension 55 is frictionally held within the fitting at the adjustment point. 55

The friction may be secured to advantage by so bending the wire that the extension 55 is out of line with the axis of the fitting in order that the resilience of the extension may be utilized to 5 secure proper friction between the parts.

The fittings 52 pass through the slots or slits within the base into the space formed by flange 57 and into pockets 58, 59, 60, 61. These pockets are provided by reversely bending strip 62 fastened to the base at its ends 63, 64. The pockets may be sufficiently contracted at their upper ranges 65 so as to give a spring effect against the lower ends of the forms, holding the forms in position as shown.

15 The walls of the pockets are intended to engage whatever form contour is presented to them, the edges of the slits in the floor forming limits to prevent undue side swinging movement of the forms within whatever frictional engaging surface is provided beneath the floor of the base.

20 The parts of the base and holder may be assembled readily for example by spot-welding the clips 38 and 39 and the retainer strip 62 to the base.

25 The fitting 52 may serve a triple purpose, not only in uniting the ends of the drying form and in providing adjustment of the ends of the form, but in cooperating with the pockets free from interference with the adjustment.

30 A boarded stocking is shown at 66 in Figure 4 upon a form having a trombone type of adjustable toe at 67. No claim is made in the present application of this toe-adjustment which is embodied in United States Patent No. 2,120,219, granted May 12, 1938 for Stocking form and support.

40 In washing and treating a pair of stockings, for example, the user fills the flask about half full of water in which the stockings are placed with the usual prescribed quantity of soap from the soap tube, or of soap flakes, closes the flask by the cap and shakes the contents back and forth over the ribs or other corrugations in the waist or/and in the bowls.

45 The resultant passage of air and soapy water through the stockings along with the rubbing of the stockings against the corrugations quickly and thoroughly cleans the stockings, which are then rinsed in the flask in changes of rinsing water. The water always left in the bottoms of the corrugation grooves permits improved circulation.

50 The stockings are next treated in the flask with a finishing material such as is used on new stockings, to deluster, finish and water proof the fabric. The chemicals for this use are provided in the second tube. Rocking the flask gives a more rapid distribution of the treating material in the water and more rapid and uniform impregnation of the stockings with this material than would otherwise be effected.

55 The stockings are next boarded and are dried on the forms. This gives a shape corresponding to that of new stockings which shows off the "finish" to excellent advantage. The treating or "finishing" material also helps to preserve the life of the stockings. As a result the user secures long life of stockings which to the end of their life have new stocking appearance.

60 It will be evident that drying of the stockings above a radiator or register is facilitated by the construction of the base, the flange about the lower edge of the base forming a hot air compartment beneath the top, and the hot air being guided up through the individual stockings by the

slits within which the stocking forms are mounted.

In view of my invention and disclosure variations and modifications to meet individual whim or particular need will doubtless become evident to others skilled in the art to obtain all or part of the benefits of my invention without copying the structure shown and I therefore claim all such in so far as they fall within the reasonable spirit and scope of my invention.

10 Having thus described my invention, what I claim as new and desire to secure by Letters Patent is:

1. A device for drying stockings comprising a base and a stocking form of bent wire whose ends are adjustably united in a tubular fitting at the leg portion of the form, supported on the base, the base consisting of a plate having a slit into which the lower end of the form including the fitting is received, with gripping walls secured to 20 the plate to engage the sides of the fitting when it passes through the slit, the slit being longer than the width of the lower end of the stocking form in minimum adjustment and the tubular fitting entering the slit, whereby the stocking 25 form is adjustable while supported in the slit.

2. A base for stocking forms having a domed portion open at the bottom for upward movement of warm air, closed at the sides and ends and slitted at the top, the slit being adapted to 30 receive the lower end of a stocking form, and means for securing a stocking form in the slit with the foot end upstanding, said means providing an opening for air to leave the domed portion through the slit, whereby warm air from the 35 domed portion will rise through the slit and at least in part circulate through a stocking on the form.

3. A base, spring retaining means within the base, a stocking form of wire having one wire end 40 bent transversely toward the other wire end at the leg end of the stocking form, an angle fitting having a tubular arm directed longitudinally of the form engaging the other wire end and having a tubular arm directed transversely from one 45 side of the form toward the other side of the form adjustably frictionally engaging and surrounding the transversely bent wire portion, the longitudinal arm of the fitting supporting the stocking form from the base and the transverse arm of the 50 fitting permitting adjustment of the form while it is supported by the base.

4. In a stocking drying device, a base provided with a slit, a stocking form including an adjustment for the spacing of the sides of the form at 55 the leg end, the stocking form being positioned with the foot end upstanding and with the leg end in the slit, and means secured to the base for removably holding the stocking form, said means engaging the stocking form in all adjusted positions and permitting adjustment of the spacing of the sides of the stocking form while the form is held in the slit.

5. In a stocking drying device, a stocking form, means including a fitting for adjusting the spacing of the sides of the form at the leg end, a base having a slit and means attached to the base and registering with the slit for removably holding the stocking form in the slit with the foot end upstanding and with the leg end in the slit, the means for adjusting the spacing for the sides being operative when the form is held by the means for removably holding the form in the slit.
